DESIGN FOR A LADY'S HANDBAG

Irene Basser and Gertrude Pins, New York, N. Y.

Application October 30, 1943, Serial No. 111,542

Term of patent 3½ years

(Cl. D87—3)

To all whom it may concern:

Be it known that we, Irene Basser and Gertrude Pins, both citizens of no country and having applied for United States citizenship, and both residing in New York, county and State of New York, have invented a new, original, and ornamental Design for a Lady's Handbag, of which the following is a specification, reference being made to the accompanying drawing, forming a part thereof.

Fig. 1 is a front view of the bag with shoulder strap in folded position to extend along upper bag portion and embodying our new design.

Fig. 2 is a rear view of the bag of Fig. 1 with carrier handle in folded over position.

Fig. 3 is a front elevational view of the bag as suspended from the shoulder strap.

Fig. 4 is a front perspective view of the bag shown in Figs. 1, 2 and 3 with the carrier handle in extended position.

We claim:

The ornamental design for a lady's handbag, substantially as shown.
